UNITED STATES PATENT OFFICE.

FREDERICK W. CHRISWELL AND ELMER T. FEHNEL, OF SEATTLE, WASHINGTON,
ASSIGNORS TO PACIFIC CAR AND FOUNDRY COMPANY, OF SEATTLE, WASHINGTON, A CORPORATION OF WASHINGTON.

CHOCK FOR LOG BUNKS.

Application filed September 5, 1922. Serial No. 586,205.

To all whom it may concern:

Be it known that we, FREDERICK W. CHRISWELL and ELMER T. FEHNEL, citizens of the United States of America, and residents of the city of Seattle, in the county of King and State of Washington, have invented certain new and useful Improvements in Chocks for Log Bunks, of which the following is a specification.

10 Our invention relates to logging chocks and the manner of securing and holding them.

The object of our invention is to improve the construction and the manner of attaching the holding member to chocks of the type originally disclosed in the patent to Knight, No. 816,339.

The object of these improvements is to make the chock and the attachment thereto stronger and at the same time simplify the manufacture and the cost of the same, and also to so secure and hold the chock in the bunk that while permitting free movement of the chock lengthwise of the bunk within the desired limits, will prevent such movement of the chock relative to the bunk as will cause displacement from the ordinary positions of use.

30 The features of our invention which are believed to be novel and upon which we desire to secure a patent will be hereinafter particularly defined by the claims.

The accompanying drawings show our invention in the type of construction which is now preferred by us.

Figure 1 is a top plan view and Figure 2 a side elevation with one end in section, of a logging bunk showing our chock combined therewith.

40 Figure 3 is a top or plan view of the chock and the manner of attaching the holding member thereto.

Figure 4 is a side elevation of a chock with the holding arm in sections.

45 In chocks of the type referred to it has been common to make these of a plate of metal bent into the angular form of the chock, and to secure the holding or retaining member, namely a chain or rod, thereto through the medium of a bolt or arm which is secured to the chock. This method of holding is apt to be weak and at the same time permits the chock when not in use be-

ing twisted around and getting out of place so that it makes trouble when the chock is 55 to be put in position for loading logs. One of the principal objects of our invention is to provide a construction which will prevent such displacement of the chock.

Figures 1 and 2 show in plan and side elevation, respectively, a bunk having our chock applied thereto. As contemplated by us, this chock is to be made of cast steel. It has the two plates 1 and 10 joined along their upper edges so as to form an inverted V- 60 shaped casting. To strengthen this we provide flanges 11 at each side of the chock and if this be necessary, additional flanges as, for instance, one in the center, as is indicated by dotted lines in Figure 3. This flange materially strengthens the chock. 65

The manner of securing the holding member to the chock consists in forming an arm 2 integral with the lower edge of the inner side of the chock. This is preferably made 70 with a central cavity 20 formed by coring. This cavity is connected with the sides of the arm by openings through which the ends of the link 3 by which it is connected with the chain 30, are passed. The link 3 is of triangular shape having the ends of the bar from which it is formed separated sufficiently to be passed over the arm 2. When the chain 30 is to be secured to the chock the link 3 is heated and its ends pounded or otherwise forced together until they meet in the cavity of the arm 2. The tips of the bar are preferably heated quite hot and when they meet within the cavity of the arm they are forced or hammered together so as to either 85 secure a butt weld or to upset the ends thereof, as has been illustrated at 31 in Figure 3. The transverse bore in the arm 2 is intended to be made of such size as to be a reasonably snug fit for the ends of the link 3. When 90 these ends of the link are pounded together while they are also hot, at or near the welding heat, they will be upset and thereby enlarged sufficiently to resist any tendency to pull out of the arm. 95

The upper web or surface of the bunk to which the chock is applied is provided with a slot extending lengthwise of the bunk and of a width to receive the arm 2. The width of this slot is indicated in Figure 3 by the 100 dot and dash lines 4. The link 3 projects

beyond the edges of this slot and thus prevents the possibility of the bunk being raised and turned crosswise.

The type of construction of the arm, together with the manner of securing the link thereto, makes a much stronger connection than that which has been commonly employed heretofore. It also is of such nature as to prevent the chock being shifted or jarred by the shaking of the car in transit, as has occasionally happened in connection with such chocks otherwise constructed.

What we claim as our invention is:

1. A chock for log bunks comprising a body having two angularly positioned plates and a holding arm integrally connected with the free end of one of said plates and adapted to extend through the top wall of a bunk, said arm having a transverse bore for the reception of a holding member.

2. A chock for log bunks having two plates secured integrally together by their ends in substantially right angular relation, a holding arm extending from the free end

of one of said plates and having a transverse bore provided between its ends with a lateral enlargement, and a holding link having its ends entering said hole and slightly displaced laterally to enter the lateral enlargement of the hole in the arm.

3. The combination with a log bunk having a longitudinally extending slot in its upper side near its ends, and chocks therefor each having substantially right angularly positioned plates adapted to rest upon the top surface of the bunk, the innermost one of said plates having an integral holding arm extending downward through the slot in the bunk top, said arm having a transverse hole positioned below the level of the top wall of the bunk, and a link forming a part of the chock holding means and entering said transverse hole.

Signed at Renton, King County, Washington, this 21st day of August, 1922.

FREDERICK W. CHRISWELL.
ELMER T. FEHNEL.
